(57) CLAIM

The ornamental design for an electrode, as shown.

DESCRIPTION

The article is an electrode suitable for affixing to the human or animal body for connection to an electro-cardiogram machine.

FIG. 1 is a top perspective view of an electrode showing my new design;

FIG. 2 is a top plan view thereof;

FIG. 3 is a bottom plan view thereof;

FIG. 4 is a side elevation view thereof, the opposite side elevation view being a mirror image;

FIG. 5 is a front elevation view thereof; and,

FIG. 6 is a rear elevation view thereof.
